DESIGN FOR A LACE OR SIMILAR ARTICLE

Dave Friedman, Hightstown, N. J., assignor to Native Laces & Textiles, Incorporated, New York, N. Y.

Application February 18, 1947, Serial No. 136,997

Term of patent 7 years

(Cl. D47—6)

To all whom it may concern:

Be it known that I, Dave Friedman, a citizen of the United States of America, residing at Hightstown, county of Mercer, and State of New Jersey, have invented a new, original, and ornamental Design for a Lace or Similar Article, of which the following is a specification, reference being had to the accompanying drawing, forming a part thereof.

The figure is a plan view of a lace showing my new design. The dot and dash lines on the drawing outline substantially the design unit, which unit is repeated in regular succession as indicated by the extensions beyond the unit boundaries.

I claim:

The ornamental design for a lace or similar article, as shown and described.

DAVE FRIEDMAN.
